Int. Cl. D13—03

U.S. Cl. D26—1 A

FIG. 6

FIG. 7

FIG. 1 is a perspective view of a modular self-commoning barrier block showing my new design;

FIGS. 2 and 3 are respectively right and left side elevational views thereof;

FIG. 4 is a top plan view thereof;

FIG. 5 is a front elevational view thereof;

FIG. 6 is a bottom plan view thereof; and

FIG. 7 is a rear elevational view thereof.

The slots are partially shown in FIGS. 1 and 4 for convenience of illustration, it being understood that the slots are uniformly continuous along the edges indicated by broken lines.

I claim:

The ornamental design for a modular self-commoning barrier block, as shown and described.
